UNITED STATES PATENT OFFICE.

FRANK E. PAYNE, OF CHICAGO, ILLINOIS, AND JULIAN N. WALTON, OF NEW YORK, N. Y., ASSIGNEES TO CRANE PACKING COMPANY, OF CHICAGO, ILLINOIS, A CORPORATION OF ILLINOIS.

CONDENSER.

Application filed March 9, 1925. Serial No. 13,964.

Our invention relates to improvements in surface condensers and other heat exchange apparatus, and more particularly to tubes therefor having renewable flaring ends.

5 In present condenser and heat exchanger practice, a large number of tubes are assembled close together and arranged so that cooling water may be circulated through the tubes and hot gases or vapor may come 10 in contact with the other side. This present practice with thin tube sheets necessarily allows only a limited depth for packing at the point where the tubes project through the tube sheets; to attempt to obtain greater 15 packing depth on tubes of the present types of condensers and heat exchangers would require tube sheets of greater thickness to allow deeper stuffing box space. Again, with present condenser assembly, employing condenser tubes which are placed flush with the 20 tube sheet, such tube ends present a sharp circular orifice to the entering circulating water. This sharp entrance orifice interferes greatly with the free, full flow of 25 water into the tube, and it is well known that where water enters such a tube at a high velocity, the entering water has a tendency to contract for a slight distance from the entering end, leaving such portion of 30 the tube partially unfilled. This results in a reduced pressure in such portion of the tube and tends to attract to such portion of the tube any particles of air which may be 35 entrained in the circulating water, with the result that this portion of the tube end frequently suffers rapid deterioration, often necessitating costly renewal of the entire tubes.

40 One object of our invention is to provide an arrangement whereby the packing depth may be greatly increased.

Another object of the invention resides 45 in providing the tubes with flaring or funnel shaped enlarged intake ends, thereby facilitating the admission of water into the tubes insuring a smooth flow therethrough and increasing the efficiency of the apparatus.

50 A further object is to provide the flared ends of the tubes with openings to eliminate the vacuum which tends to form and thereby prolong the life of the tubes.

An additional object is to provide means for reducing the waste, caused by replace-

ment of the tubes, by constructing the tubes with renewable ends at the inlet end. When 55 the detachable ends have deteriorated, they may be renewed, thereby effecting a saving of the larger portion of the old tube. The renewable ends may be applied to existing 60 types of condensers after cutting off the worn out ends and without materially altering the tube sheets, or they may form part of an initial installation comprising part of an improved two-part condenser tube.

Other objects are to provide a construction 65 of this character, whereby a high vacuum may be maintained, and the necessary expansion and contraction provided for with such two-part tubes.

In the accompanying drawings, we have 70 illustrated several embodiments of the invention.

Fig. 1 is an elevation, partly in section, of 75 part of a condenser showing one form of improved condenser tube.

Figs. 2 and 3 are modifications thereof on a somewhat larger scale.

Fig. 4 is another modification.

Fig. 5 is a sectional elevation of a further modified renewable end.

The condenser comprises the usual end sheets 10, 11, having openings therein for the condenser tubes and one or more perforated supporting plates 12, in an intermediate position, to prevent sagging of the 85 tubes.

Each condenser tube, in the form shown, comprises a two-part construction, one of which is a long condenser tube 13, which may be practically the same as condenser 90 tubes now in use, except that it may be somewhat shorter. Such tubes are made usually of brass alloy. Each of said tubes passes loosely through an opening 14 in the tube sheet 11, said opening being enlarged 95 and screw-threaded to receive the ferrule 15.

Packing is usually compressed against the shoulder in this opening by said ferrule, but in the present case such packing is dispensed with, and the ferrule 15 soldered or tinned 100 to tube 13, or the tube may be expanded or rolled in screw ferrule 15, whereby when the ferrule is screwed tightly into the tube sheet an air tight joint is maintained.

The other end of the condenser tube consists of a short section of tubing 16 having

its outer end flared or expanded, as shown at 17, said tubing passing through a suitable opening 18 in the tube sheet 10. This short section is further expanded in opening 18 in the tube sheet 10. The inner end of the tubing 16 is turned inwardly to form a flange 19 (as shown more fully in Fig. 2, which is the same in this respect) against which suitable packing 20 may be forced, causing said packing to expand and press against tube 13, thereby providing a sliding joint which is also air tight. The packing is preferably soft metallic packing in the form of an endless ring, or it may be fibrous packing, or a combination of the two, depending on the class of service. Where metallic packing is used to prevent electrolysis, the rings are slipped over the tube 13 (Fig. 1), and thereafter swaged in place by means of a length of pipe, telescoping tool, or some suitable swaging tool. As this two-part condenser tube expands or contracts, the larger end 16 thereof cannot be drawn inwardly or forced outwardly through tube sheet 10 because it is secured against movement by being expanded in tube sheet 10. The other end is held to the tube sheet 11 by the screw-threaded engagement of the ferrule 15, which constitutes, in effect, an integral part of the tube 13. The expansion and contraction is therefore taken up in the sliding joint provided by the packing.

Cooling water flows through the tubes in the direction indicated by the arrows in Fig. 2, and the flaring inlet 17 has the effect of reducing, to a considerable extent, the tendency of the stream to contract as it enters the tubes, thereby reducing the partial vacuum otherwise formed. In addition, the projecting end 17 may be provided with one or more holes or openings 21 therein, which substantially eliminate said partial vacuum by causing the pressure between the inside and outside of the end 17 to become equalized, and therefore, to a large extent, eliminate the wear due to the action of the air on the upper inner surface of the tube. The flaring ends also facilitate the admission of water into the tubes by greatly reducing the friction between the water and the intake ends of the tubes, thus improving the operation of the apparatus.

If such slight wear as takes place, continues for a sufficient time to require renewal of the metal, all that is necessary is to renew the part 16. This may be done by pulling out the section 16, inserting a new section, slipping a packing ring over the end 13 and swaging the packing sufficiently to insure a tight joint. Should the end of long tube 13 be disintegrated, the short section may be extended a greater distance throughout the tube sheet 10 to a point on tube 13, where the same has not been affected, as illustrated in Fig. 3.

In Fig. 2, one end of the condenser tube 22 is expanded or rolled into a correspondingly shaped opening in the tube sheet 11. The other end has a sliding connection with an enlarged section, similar in all essential respects to the renewable section, previously described. The inner surface of the tube 16 may be roughened somewhat by pressing the metal inwardly in places, or by rolling grooves therein, as shown at 23 in Fig. 2, the said roughened portion serving to prevent movement of the packing upon expansion of the tube. Two metallic packing rings 20 are illustrated in this figure also, but it will be understood, of course, that any suitable number may be employed in connection with any of the figures described herein, and also that fiber expansion members 24, or other types of packing may be employed.

In Fig. 3, the condenser tube 25 has its end 26 expanded or rolled into the enlarged opening in the tube sheet 11. The renewable tube section 27 may be a short length, such as previously described, or it may be somewhat longer, as shown in this view, merely for the purpose of illustrating various lengths that may be employed. It will be seen that by using the long renewable sections a greater area of cooling surface is provided. The outer flared end, instead of projecting beyond the tube sheet 10, is preferably rolled or expanded into a flaring opening in said tube sheet. Packing rings 28, similar to those previously described are used to form an air tight sliding joint between the larger and smaller tube sections. A plurality of packing rings are preferably employed in this instance, which, when swaged into place, form an air tight sliding joint. In order to renew this type of condenser tube, the sections may be pulled through the respective openings in sheets 10 and 11. In installing the two tube sections, said sections are introduced from opposite ends of the condenser, and thereafter the packing rings 28 are swaged in place, or the two-piece tube may be assembled, packed and then placed in the condenser, after which the ends may be expanded in tube sheets 10 and 11.

In connection with the foregoing renewable tube ends, it will be seen that although a larger hole in the tube sheet 10 is required, there is room for much larger holes either in the tube sheets of an existing installation or in the sheets of an entirely new condenser, since the enlarged holes do not require the removal of more metal than was required in providing the screw-threaded openings, previously employed. Furthermore, no ferrules are necessary in this end of the condenser so that the expanded ends of the tubes may be fairly close together without inconvenience.

Fig. 4 illustrates an adaptation of our in-

vention to a typical present day structure. The threads of the enlarged portion of the opening in the tube sheet may be removed and renewable tube 29 expanded in position 5 therein, as shown. The condenser tube 30 is then positioned and packing 31 is inserted to make an air tight sliding joint. It will be seen that this construction does not weaken the tube sheet in any respect, and that the 10 flaring end of the section 29 prevents the deteriorating effects on the inner end of the condenser tubes, as in the previously described modifications.

In Fig. 5, a somewhat similar construction 15 is shown comprising a small tube section 32 and a renewable section 33 with a plurality of packing rings 34, having fiber expansion rings therebetween, as in Fig. 2. The smaller tube in this case terminates in 20 or near the tube sheet 10, although it may be shorter, and in order to avoid an abrupt shoulder at the end of said smaller tube, a filling ring or arcuate nozzle 35 may be inserted having a tapering opening therein to 25 provide a smooth contracting nozzle for the inflowing water.

A funnel shaped nozzle, somewhat as shown in Fig. 5, may be used also in connection with the construction illustrated in 30 the other figures. For example, in Fig. 2, I have indicated in dotted lines such a ring or adaptor 35 which fits within the larger outer tube section and abuts against the end of the smaller inner tube section to provide 35 a gradual contraction of the inner diameter of the composite tube through which the water flows, thereby offering less resistance to said flow and minimizing the tendency to create a partial vacuum near the end of said 40 inner tube.

The available space for packing the ends 45 of condenser tubes is comparatively small, as will be seen from Fig. 1. Condensers are usually made with one or more supporting plates 12 between the tube sheets to prevent excessive vibration of the condenser tubes, but some vibration occurs in many cases, and there are instances where the supporting 50 plates, through oversight or poor design, have been omitted. As a result, such excessive vibration of the tubes makes it difficult to obtain a tight joint at the ends of the tubes, under the old practice. With the improved construction, described herein, many 55 more rings of packing may be employed than would be possible in the limited space available in the tube sheet. As shown in Fig. 2, for example, the thickness of the packing in the direction of the length of 60 the condenser tube is greater than the entire thickness of the tube sheet, thereby making it possible to maintain a tight joint, even with considerable vibration of the tubes.

Figs. 4 and 5 also show thicknesses of 65 packing greatly in excess of what would be

possible under the old practice, without making the tube sheets prohibitively thick and correspondingly heavy.

Various changes may be made in the different forms described without departing 70 from the spirit of the invention, and features illustrated in connection with one form may be used with any of the others, such, for example, as the holes in the flaring intake ends which may be provided in all cases 75 where said intake end projects beyond the tube sheet.

What we claim as new is:

1. A condenser having a tube sheet and a tube with a renewable end, said renewable 80 end having a flaring outer extremity being secured to said tube sheet and extending beyond the end of said tube.

2. A condenser having tube sheets, and a tube received within an opening in one of 85 said tube sheets and terminating short of the other tube sheet, said tube having a renewable end secured to said other tube sheet and extending beyond the end of said tube, and said other tube sheet.

3. A condenser comprising a tube sheet and a tube having a removable flaring liquid intake end passing through said tube sheet and projecting beyond said tube sheet.

4. In a condenser, a tube sheet having an 90 opening therein for a condenser tube, said condenser tube consisting of two tubes of different diameters having their ends telescoped, one over the other, with a clearance space between said telescoping ends, and 95 packing in said clearance space, whereby the thickness of the packing longitudinally of said tubes may exceed the packing space available in the opening in said tube sheet, the combined lengths of said two tubes in 100 operative assembly being greater than either 105 of said tubes.

5. A condenser tube having a flaring telescoping section to prevent the formation of a partial vacuum adjacent the intake end 110 thereof.

6. A condenser having a tube therein with a renewable end, the inner surface of which is exposed to the water entering said tube and a metallic packing maintaining an air-tight joint between said tube and end.

7. In a condenser tube, a renewable end having an inwardly turned flange at one end, and a flaring opening at the other end.

8. A condenser tube having a renewable 120 end comprising a tube section of larger diameter than the main tube and projecting beyond the end thereof, with metallic packing between said tube sections.

9. A condenser tube having a renewable 125 end comprising a tube section of larger diameter than the main tube, with metallic packing between said tube sections, the larger section having a flared outer end projecting beyond the end of said main tube.

- 4
10. A condenser tube having a flared outer end with openings therethrough outside of the tube sheet to prevent the formation of a partial vacuum in the end of said tube. 30
- 5 11. A condenser tube having a ferrule at one end and having a larger renewable tube section at its other end and extending beyond said end. 35
- 10 12. A condenser tube having a ferrule secured at one end thereof and having a larger renewable tube section at its other end and extending beyond said end. 40
- 15 13. A condenser comprising tube sheets having openings therein, a condenser tube passing through one of said openings, secured therein and terminating short of the other tube sheet, and a renewable section passing through the opening in the other tube sheet and having an air tight sliding connection with said first tube. 45
- 20 14. A condenser comprising tube sheets having openings therein, a condenser tube passing through one of said openings, secured therein and terminating short of the other tube sheet, and a renewable section pass- 45
- 25
- ing through the opening in the other tube sheet and having an air tight sliding connection with said first tube, said enlarged section having a flaring outer end with openings therein outside of said tube sheet. 30
15. A condenser comprising a tube sheet having an opening therein, a tube, and a ferrule secured in said opening and surrounding the end of said tube, said ferrule having a portion spaced from said tube, 35 and packing in said space providing a sliding air-tight joint. 40
16. A condenser comprising a tube sheet, a tube having a renewable section, said section surrounding one end of the tube and being secured in an opening in the tube sheet, said section being provided with an inner shoulder, and packing disposed against said shoulder and between said tube and section to form an air tight sliding joint. 45

In testimony whereof, we have subscribed our names.
